UNITED STATES PATENT OFFICE.

MICHAEL M. SWEETMAN, OF KANSAS CITY, MISSOURI.

DESIGN FOR A LAMP-BODY.

SPECIFICATION forming part of Design No. 32,309, dated March 6, 1900.

Application filed February 9, 1900. Serial No. 4,698. Term of patent 7 years.

To all whom it may concern:

Be it known that I, MICHAEL M. SWEETMAN, a citizen of the United States, residing at Kansas City, in the county of Jackson and State of Missouri, have invented and produced a new and original Design for Lamp-Bodies, of which the following is a specification, reference being had to the accompanying drawings, forming part thereof.

Figure 1 is a side elevation of the lamp; and Fig. 2, a similar view, partly in section.

As shown in the drawings, the leading and material features of the design comprise the rounded or semispherical hood A, surmounted by a cap B, while at the lower end or edge of the hood-section A is a ring or band C, and below this is a second ring or band D of smaller diameter.

Extending through rim C at opposite points are members E F, each carrying at its outer end a fitting G, and connected to said fitting and extending up therefrom are curved mem-

bers H H, which in turn are connected to a fitting I. A vertically-disposed member J is secured to said fitting I, and a fount K is carried by the upper end of said member J.

A hook L surmounts the fount, as shown.

To the inner end of member F there is secured a fitting M, and from said fitting there depends a member N, the lower end of which is curved inwardly, as shown, its end being provided with a fitting O, having an upward extension P.

Having thus described my invention, what I claim is—

The design for a lamp-body substantially as shown and described.

In witness whereof I hereunto set my hand in the presence of two witnesses.

MICHAEL M. SWEETMAN.
